UNITED STATES PATENT OFFICE.

LEON LEROY POSTON, OF COUNCIL BLUFFS, IOWA.

PORCELAIN TOOTH-FACING.

No. 799,495.

Specification of Letters Patent.

Patented Sept. 12, 1905.

Application filed October 8, 1904. Serial No. 227,084.

To all whom it may concern:

Be it known that I, LEON LEROY POSTON, a citizen of the United States, residing at Council Bluffs, in the county of Pottawattamie, State 5 of Iowa, have invented an Improvement in Porcelain Tooth-Facings, of which the following is a specification.

The object of my invention is to provide a tooth that can be slipped on or off a backing o and at the same time be made at little cost and also be strong and readily replaced by a new one when broken.

The construction, arrangement, and attachment of parts are as hereinafter described, reference being had to the accompanying drawings, in which—

Figure 1 is a perspective view of the porcelain facing or tooth proper. Fig. 2 is a central longitudinal section of the same. Fig. 3 o is a perspective view of the metal backing for the tooth, the same comprising an angular plate and a rod secured to its back. Fig. 4 is a side view of the backing. Fig. 5 is a longitudinal section of the porcelain tooth and the backing, together with the filling or gold solder applied to the backing. Fig. 6 is a horizontal section on the line 6 6 of Fig. 5.

As indicated in Figs. 1 and 2, the porcelain tooth or facing 1 has a back constructed in angular form—that is to say, with a flat vertical face 2 and a horizontal shorter portion or shelf 3. These parts are shown arranged at a right angle to each other; but they may be at a little less than a right angle. In the 35 vertical back 2 is formed a dovetail groove 4, which extends its entire length and down into and below the shelf 3, its terminal or socket being indicated by 4^a. The metal backing for the tooth 1 is composed of an angular metal 40 plate, formed of a vertical portion 5 and a horizontal or shelf portion 5^a, together with a rod or stout wire 6, which is soldered to the back or vertical member 5 and extends below it, as indicated at 6^a, Figs. 3 and 4. These 45 parts 5 5^a and 6 6^a are constructed of gold, platinum, or other equivalent metal. The rod 6 is adapted to slide and fit somewhat closely in the vertical dovetail groove 4, and its lower end 6^a enters the socket 4^a, while the 50 plate 5 5^a conforms to and is made to fit closely to the corresponding parts 2 and 3 of the tooth 1. It will be understood that the flexi-

bility of the backing-plate permits the latter to be bent and fitted with the required accuracy. When the parts have been duly fitted, 55 the backing, consisting of the angular plate and the rod attached to it, may be removed and filled, as indicated at 7, Fig. 5, after which it may be set in position on the tooth, and the latter is then ready for attachment to the part 60 by which it is supported in the mouth.

By the construction and arrangement of parts above described I secure great strength of engagement or fastening between the tooth or facing and the metal backing, and an im- 65 portant feature of the attachment is the extension of the rod 6 below the angular plate and into a socket formed in the body of the facing below the horizontal shelf or shelf portion 3. It will be apparent that this re- 70 sult and advantage are attained in part by reason of the fact that the socket 4^a is formed in the thickest and strongest portion of the tooth 1. It is apparent that a dentist may construct the backing for himself by simply 75 soldering a piece of wire of proper gage to a plate bent at the proper angle. The wire is made of standard size, and of course the angle of the shelf or shoulder 3 to the flat back 2 is absolutely the same for each class, so that 80 the parts may be interchanged, thus providing for easy replacement when a part is broken.

What I claim is—

The improved dental attachment comprising 85 a porcelain tooth having its back constructed in right-angular form, the vertical portion having a dovetail groove which extends down below the horizontal or shelf portion and terminates in a socket, and a right- 90 angular plate having a rod secured to and extending below it, the said plate and rod being fitted to the tooth proper and the rod being held in the said groove and extending below the shelf into the said socket, as shown and 95 described.

In testimony whereof I have signed my name to this specification in the presence of two witnesses.

LEON LEROY POSTON.
